CRIMPING DEVICE

Paul Esselmann, Wolfen, Kreis Bitterfeld, Karl Kösslinger, Dessau, and Paul Saffert, Wolfen, Kreis Bitterfeld, Germany, assignors to I. G. Farbenindustrie Aktiengesellschaft, Frankfort-on-the-Main, Germany

Application April 1, 1939, Serial No. 265,484
In Germany June 23, 1937

3 Claims. (Cl. 19—66)

Our present invention relates to a device for crimping a torn sliver of rayon staple fibers. This application is a continuation-in-part of our application Serial No. 214,268, filed June 17, 1938.

5 Bands of continuous artificial fibers are converted into extensible slivers of staple fibers by cutting or tearing. The individual staple fibers of these slivers, especially when they have been produced by a stretching and tearing process, are quite smooth and in many cases this is very disadvantageous in the further working up of the fibers. Such slivers are difficult to mix, they have only a low cohesion and frequently break, because they lack the crimped character which 10 belongs, for example, to natural wool.

Attempts have been made to crimp these smooth fibers by means of finely fluted pressure rollers. Devices have also been proposed for crimping these artificial textile fibers, in which 20 the fibrous goods are led from a pair of delivery rollers against a spring loaded blade, whereby the fibers are compressed and crimped. However, such devices have never operated satisfactorily on a commercial scale.

25 It has also been proposed in the working up of bands of long fibers, such as flax, hemp, jute and the like, to produce a crimping by forwarding the band of fibers by means of a pair of rollers against a yieldable resistance which covers a 30 U-shaped guide trough. This device cannot be used for crimping a band of artificial fibers, because the fibers are deflected laterally, and, especially in the case of slivers consisting mainly of parallel fibers, become tangled owing to this 35 lateral deflection.

Our present invention has for one object to provide a device in which the delivery rollers, collecting trough and the flap which closes the trough are so constructed as to form a very 40 tightly enclosed space in order that the slivers of cellulose artificial wool, even those in which the individual fibers are of very fine titer, are very uniformly crimped.

Another object of our invention is the provision 45 of extensions on the sides of the collecting trough which fit closely within grooves in the delivery rollers so as to prevent the deflection of parts of the sliver at that place. In the collecting space thus formed the pressure increases 50 owing to the bunching-up of the fibers therein until the adjustable loading of the flap is overcome by the internal pressure and the fibrous material crimped thereby is allowed to escape. The degree of crimping can be regulated by adjusting the loading of the trap.

Further objects of our invention will appear from the description following hereinafter.

Reference is made to the accompanying drawings in which

Figure 1 is a sectional elevation of the crimping device, 5

Figure 2 is a partial plan view of the device shown in Figure 1,

Figure 3 is a sectional elevation of a modified form of the crimping device shown in Figure 1, 10

Figure 4 is a partial plan view of the device shown in Figure 3, and

Figure 5 is a diagrammatical view of the tearing or drafting device including three drafting sets and a crimping device. 15

In Figure 1, *a* denotes an extensible sliver of staple fibers produced by tearing, and *1* and *2* are delivery rollers by which the sliver is fed into a collecting trough *9*. The trough is closed at one end by the rollers *1* and *2*, into grooves *1a* and *2a* of which rollers fit the tongue-shaped ends of the trough (see Figure 2). It has been found advantageous to fix a leather tongue or another elastic packing *6* by means of a screw *7* to the floor *8* of the trough *9* in order to secure a close fit against the lower roller *2*. The collecting trough *9* is closed by a flap *3* pivotally suspended between the walls of the trough about the pivot *10*. A lever arm *4* mounted on the flap *3* carries a weight *5*, by means of which the pressure in the trough may be adjusted by suspending the weight *5* from one or another of the notches *11*. 20

In a modified form of the apparatus (see Figures 3 and 4), with which equally good results 35 are obtainable, the sliver to be crimped is fed through a U-shaped groove in the lower roller *2* and held in this groove by a corresponding shaping of the upper roller *1*. The floor *8* of the collecting trough *9* in this modification engages in the groove of the lower roller, advantageously by means of a leather lining *6*, and the side walls of the trough lie closely against the surfaces of the lower and upper rollers. Thus, the complete closure of the collecting space 40 is also attained in this case. 45

Several crimping devices of this kind may be arranged in series with their traps similarly or differently loaded according to the kind of crimping desired. 50

In Figure 5, *b* is a can in which a bundle of continuous artificial fibers is contained and transported. The bundle is fed to a multiple tearing device comprising, for instance, three sets of rollers *12—13*, *14—15* and *16—17*. The 55

speed of these rollers is so arranged that each succeeding set runs faster than the preceding set. The rollers 12, 14 and 16 are driven while 5 13, 15 and 17 are kept rotating by the bundle of fibers itself, which engages the rollers with friction. Rollers 12, 14 and 16 may be fluted, that is to say the roller surface may be provided with grooves extending parallel to the axis of the roller. The first tearing occurs between the sets 10 of rollers 12-13 and 14-15, the tearing distance being c . The bundle is reduced to a sliver in which the individual fibers are of comparatively long and uneven staple length. A second tearing therefore occurs between the sets of 15 rollers 14-15 and 16-17, the tearing distance in this case being reduced to d . These preliminary tearing operations lead to a sliver having a more or less uniform staple length. In these tearing operations the individual fibers 20 are broken with as little damage as possible since the unloaded rollers 13, 15 and 17 exert only a minimum of pressure on the bundle of fibers. The sliver is then led to a further set of tearing rollers 18, 19, 20 and 21. Again the 25 smaller rollers 20 and 21 are driven while rollers 18 and 19 are adapted to exert the pressure necessary to break the fibers in the sliver. For this purpose the rollers 18 and 19 are held down by the weights 22 and 23. The tearing distance 30 is e , which is still shorter than d . It has been found that for this short tearing distance the weighted rollers are better than the drafting devices 12-13, etc. They ensure a complete reduction of the sliver to the desired short 35 staple length. The torn sliver is now led to the crimping device (1, 2, 3, 5, 9 inclusive) described above with reference to Figures 1 to 4. b_1 is a can for receiving the crimped product.

We claim:

40 1. In an apparatus of the character described

a device for crimping a continuous sliver of rayon staple fibers comprising, in combination, an upper delivery roller, a lower delivery roller having a U-shaped groove, a collecting trough, the side walls of said trough lying closely against 5 said rollers, the floor of said trough engaging in said groove, a trap pivotally suspended within said trough and capable of closing that side of said trough which is not closed by said rollers, and a lever affixed to said trap carrying an 10 adjustable weight.

2. In an apparatus of the character described 15 a device for crimping a continuous sliver of rayon staple fibers comprising, in combination, an upper delivery roller, a lower delivery roller 15 having a U-shaped groove, a collecting trough, the side walls of said trough lying closely against said rollers, the floor of said trough and an elastic packing affixed to said floor engaging in said groove, a trap pivotally suspended within 20 said trough and capable of closing that side of said trough which is not closed by said rollers, and a lever affixed to said trap carrying an adjustable weight.

3. In an apparatus of the character described 25 a device for crimping a continuous sliver of rayon staple fibers comprising, in combination, an upper delivery roller, a lower delivery roller having a U-shaped groove, a collecting trough, the side walls of said trough lying closely against 30 said rollers, the floor of said trough and a leather lining affixed to said floor engaging in said groove, a trap pivotally suspended within said trough and capable of closing that side of said trough which is not closed by said rollers, and 35 a lever affixed to said trap carrying an adjustable weight.
